Des. 212,176
Patented Sept. 3, 1968

212,176

COMBINED FOOD SERVICE AND REFRIGERATED CABINET

Theodore C. Lambertson, Millbrae, Calif., assignor, by
mesne assignments, to Robert E. Church and Conrad J.
Klein, and Commonwealth National Bank of San
Francisco

Filed July 3, 1967, Ser. No. 7,698

Term of patent 14 years

(Cl. D80—2)

FIG—1

FIG_2

FIG_3

FIG_4

FIG. 1 is a view in perspective of a combined food service and refrigerated cabinet showing the features of my new design;

FIG. 2 is a top plan view of the same;

FIG. 3 is a front elevation view of the same; and

FIG. 4 is an elevational view taken from the end opposite that shown in FIG. 1.

The rear is plain and unornamented as indicated in FIG. 4.

I claim:

The ornamental design for a combined food service and refrigerated cabinet, substantially as shown and described.
